STEAM GENERATOR

James A. Standing, Detroit, Mich.

Application June 14, 1943, Serial No. 490,759

5 Claims.

(Cl. 219—38)

The present invention relates to steam generators, specifically for house heating, although of much broader application.

Among the objects of the invention is a steam generator utilizing electric heating in a more efficient manner than has been heretofore known.

Another object is a generator designed specifically for electric heating and therefore capable of transferring more efficiently electrically generated heat to the contained water.

Other objects and advantages will be apparent to those skilled in the art upon reference to the following description and the accompanying drawings in which

Figure 1 is a vertical central sectional view of a generator according to the present invention.

Figure 2 is a plan view of the top plate.

Figure 3 is a plan view of the upper side of the bottom plate.

Figure 4 is a horizontal sectional view showing the heater arrangement and

Figure 5 is a wiring diagram.

Figure 6 is a sectional view of an alternative form of circulator.

As indicated in the drawings, the generator may consist of a water container formed of the side walls 10, bottom 11 and top 12, suitably insulated as indicated at 13. While the sides, top and bottom may be permanently fixed together, as by welding, it is preferred to suitably groove the top and bottom as at 14 for the reception of the side walls and hold these parts together with a plurality of rods 15, suitable gaskets or other sealing means being used.

In the top plate 12, it is proposed to provide openings for the customary pressure gauge 16, steam outlet 17 and return 18, safety valve, and also a thermostatic regulator 20. The two openings for the water coil 45 are also of course provided and the other opening shown may be used for a water inlet.

In the side wall may be mounted a water gauge 19, while at a suitable location may be placed the drain 50. The bottom plate 11, as shown in Figs. 1 and 3, will be provided with a series of openings 25 arranged near the periphery and an equal number of openings 26 arranged in a group located centrally of the plate as clearly shown in Figure 3, and each of the openings 25 is connected to an opening 26 by a relatively small U-tube 27, located under the bottom plate 11 but opening to the inside of the water reservoir.

As shown, the bottom plate 11 will be supported upon a hollow base divided by an horizontal partition 30 to form a heater chamber 31 and a lower

chamber 32. In the chamber 31 will be placed a plurality of electric heaters 33 and 34 of which the heaters 33 may be distributed as indicated in Figure 4 and the heater 34 located in the center under the grouped inward ends of tubes 27.

These heaters 33 and 34 may be supplied with electric current from any suitable source, but it is preferred to supply them with direct current, and at much lower voltage than is ordinarily available.

Accordingly, there is shown in Figure 1 a motor-generator combination 40 located in the chamber 32, and protected from the heat developed by heaters 33 and 34 by a layer of insulation 41.

Since most house heating generators are used to heat water for other uses, a suitable water coil is shown at 45 as extending into the generator.

As indicated by the diagram of Figure 5, the current supply to heaters 33 is controlled by the thermostat 20 while the supply from the main supply line 41 to heater 34 may be controlled by a second thermostat 20A. The reason for this arrangement is that the single central heater 34 will supply sufficient heat to maintain usually the temperature of the water near the boiling point so that the heaters 33 are not necessary except when cold water is introduced or in first starting the generator. The heaters 33 will also cut in during extreme demands upon the heating system.

The thermostat 20 will be located in the space to be heated and starts and stops the motor-generator in accordance with the demand for heat in said space.

The heat generator while intended primarily for space heating may also be used in mild or warm weather solely for water heating and in such use, the heaters 33 will be disconnected by means of a suitably located switch (not shown). The heater 34 will then automatically maintain the temperature of the water in the boiler 10 at the temperature desired for heating coil 45.

It will be noted that the pipes 27 are only one form of circulator or "percolator" means that may be used to confine temporarily a small body of water for intense heating, as other such means may be used.

In Figure 6 is shown an alternative form that presents advantages over the pipes in that it among other things, admits of easy cleaning.

In this figure, the bottom 11 of the reservoir will be provided with tapped openings into which may be threaded a tube 127 of fairly large diameter provided with several internal lugs 128 near

its bottom. Into the tube 127 is inserted a smaller tube 129 with its lower end substantially flush with the bottom end of tube 127 and its upper end extending well up into the reservoir. This tube 129 will have its lower end flared as at 130 and serrated as at 131, and will be limited in its upward movement by the lugs 128. A suitable cap will then be used to hold the two tubes in place.

While only one such alternative form of circulation is shown, it is obvious that a plurality of them may be used if desired and such is contemplated.

Now having described the invention and the preferred embodiments thereof, it is to be understood that said invention is to be limited, not to the specific details herein set forth, but only by the scope of the claims which follow.

I claim:

1. A steam generator for space heating consisting of a water reservoir, a heater chamber beneath said reservoir and containing heating means, said heating means being spaced from the bottom of said reservoir, and a plurality of radially arranged water circulation pipes open to said reservoir located in the space between said heating means and said bottom.

2. A steam generator for space heating consisting of a water reservoir, a heater chamber beneath said reservoir and containing heating means, said heating means being spaced from the bottom of said reservoir and a plurality of water circulation pipes leading from near the periphery to near the center of said reservoir and passing through the space between the heating means and the bottom of the reservoir.

3. A steam generator for space heating consisting of a water reservoir having a heater cham-

ber below, electric heating means in said chamber and arranged in an annulus, a second electric heating means arranged centrally of said annulus, separate electric circuits for supplying current to the first and second heating means and separate control means in said circuits and including thermostatic means, the thermostatic means in the first circuit being adapted to be affected by the temperature of the space to be heated and that in the second circuit being adapted to be affected by the temperature of the water in said reservoir.

4. A steam generator for space heating consisting of a water reservoir, a heater chamber beneath said reservoir and containing heating means, said heating means being spaced from the bottom of said reservoir and a plurality of water circulation pipes leading from near the periphery to near the center of said reservoir and passing through the space between the heating means and the bottom of the reservoir, the outer ends of said pipes being substantially flush with the bottom of said reservoir while the inner ends extend upward a substantial distance from said bottom.

5. A steam generator for space heating consisting of a water reservoir, a heater chamber beneath said reservoir and containing heating means, said heating means being spaced from the bottom of said reservoir and a plurality of water circulation units including means for temporarily confining a small quantity of water adjacent a heating means whereby to subject said small quantity to intense heating, said units having their water inlets substantially flush with the bottom of said reservoir and their discharge outlets a substantial distance above said bottom.
